UNITED STATES PATENT OFFICE

164,140

FRAME OF A BABY WALKER

Cedric C. Stack, Elwood, Ind.

Application August 3, 1950, Serial No. 11,582

Term of patent 14 years

(Cl. D14—14)

To all whom it may concern:

Be it known that I, Cedric C. Stack, a citizen of the United States and a resident of Elwood, county of Madison, and State of Indiana, have invented a new, original, and ornamental Design for the Frame of a Baby Walker, of which the following is a specification, reference being had to the accompanying drawing, forming a part thereof, in which Fig. 1 is a perspective view of the frame of a baby walker showing my new design; Fig. 2 is a front view of the same on substantially the scale of Fig. 1; and Fig. 3 is a top view thereof on the scale of Fig. 2.

I claim:

The ornamental design for a frame of a baby walker, substantially as shown.

CEDRIC C. STACK.
